UNITED STATES PATENT OFFICE.

LOUIS SAVART, OF PARIS, FRANCE.

SOUND-PRODUCER.

1,168,967.

specification of Letters Patent. Patented Jan. 18, 1916.

Application filed January 13, 1915. Serial No. 2,052.

To all whom it may concern:

Be it known that I, LOUIS SAVART, a citizen of the French Republic, residing at Paris, France, have invented certain new and useful Improvements in Sound-Producers, of which the following is a specification.

The majority of horns used on motor cars generally comprise reeds which break up into regular waves the current of air blown therethrough. It is found in practice that the sound emitted by such horns is discontinuous or interrupted. This is due to the fact that the current of air has not a definite and constant pressure, so that pulsations or excesses of pressure are produced in the column of air blown in, which cause the reed to adhere to its seat (this is particularly the case in horns which are worked by air pumps).

This invention has for its object to obviate the drawbacks in question, and relates to a sound producer which has been designed for improving the working of horns in which a reed is used. To that end, instead of connecting the sound tube or the amplifying bell mouth directly to the reed, the conduit terminating at the same is controlled by a vibrating tongue extended accordingly, and the whole is inclosed in an air tight box which has no connection with the atmosphere.

In the accompanying drawing—Figure 1 shows diagrammatically an arrangement of the system according to this invention. Fig. 2 shows in longitudinal section and in cross-section, and Fig. 3 in longitudinal section, in cross-section and in plan constructions of the sound producer, diagrammatically shown in Fig. 1.

According to this invention, the chamber *c* containing the reed, is closed in an air tight manner, and the sound is emitted through a tube *b* arranged in the said chamber *c*, the inner opening of the said tube being controlled by the tongue *e* of the reed suitably extended for the purpose.

When air is blown in through the tube *a*, the tongue *e* of the reed is raised, thereby admitting the air into the chamber *c*, there being no outlet from the chamber save that into *b*, which must be reached under the tongue *e*. This air exerts a pressure on the tongue *e* in opposition to the air forced into the tube *a*. This counter pressure is obvi-

ously less than that of the air blown in through the tube *a*, but it acts on a larger area of the tongue *e*, as shown in Fig. 2, and it has a tendency to force the tongue *e* against its seat and thus close the air tube *a*. At the moment when the tongue *e* is brought close to its seat there is an equalization of these two pressures resulting in the tongue *e* remaining in a slightly raised position, thus allowing a direct communication of the tubes *a* and *b* for an injection of air to produce a sound wave in the latter tube. This state of equilibrium, however, is only momentary for the column of air passing from the chamber *c* into the tube *b* is interrupted at short intervals by the vibration of the reed *e*, and since the inertia of the air column keeps the column in motion, alternate condensation and rarefactions are produced which create a sound of the pitch corresponding to the rate of vibration of the reed. Similar phenomena take place again, the air getting into the emission pipe *b* in order to produce therein a new vibration, and so on.

In the constructions illustrated, see Figs. 2 and 3, the compressed air supply pipe *a* and the emission pipe *b* terminating at an amplifying bell-mouth are arranged so that their openings are concentric or in one and the same axis of symmetry, so that the orifice of one is embraced by the annular surface surrounding the orifice of the other.

In the construction shown in Fig. 2, the orifices are of rectangular shape. The air supply pipe *a* is provided with a flat rectangular opening and is partly surrounded by the wall of the emission pipe *b* which also has a flat rectangular opening in the same plane as the opening in the air pipe *a*. The tongue *e* engages with these two openings. A closed chamber *c* surrounds the whole and connects the air compressor pipe *a* to the emission pipe *b*.

Where a compression bulb is utilized to produce a blast, a valve *f* can be used to enable the fluid to return to the said bulb part.

In the construction shown in Fig. 3, the orifices of the pipes are circular. The air supply pipe *a* has an elbow bend, around the wall of which is arranged the annular conduit *b'* communicating with the emission pipe *b*. The whole constitutes a block on which the tongue *e* is arranged so as to cover the concentric orifices of the said pipes *a* *b*. The return valve is shown at *f*. The device

thus arranged is mounted in a closed box *c*. The pipes engage with rubber washers *g* so as to register with connections mounted centrally on the fixed and movable ends of the box *c*.

It will be seen that in the construction shown in Fig. 3, the plane of the openings with which the tongue *e* engages is arranged at a lower level than the upper plane or ridge *h* of the part. The tongue *e* is consequently surrounded by a raised flange *h*.

When the air escapes after having raised the tongue *e*, it strikes the said flange *h* which stops it. This results in an increase of pressure under the tongue which is then raised still more, until it has passed the flange *h* surrounding it. At this moment the air passes into the chamber *c* and acts as already described.

It will be seen further that in such a construction of sound producer, the opening of the tongue *e* is effected partly by the pressure of the air blown into the apparatus, while its closing is due in part to the counter-pressure exercised by the fluid which has passed into the closed chamber *c*; it being understood that the elasticity of the tongue itself plays a certain part in each case. The periods of opening and closing determine the sound waves produced in the tube *b*.

In the construction shown in Fig. 3, the sound producer arranged in the axis of the

casing *c* is molded in a single piece of ebonite.

The above constructions are given merely by way of example and the shapes, material, dimensions, details and applications can vary according to circumstances, without departing from this invention.

What I claim as my invention and desire to secure by Letters Patent is:—

1. In a sound producer, an air supply pipe and an emission pipe co-extensive therewith, said pipes having adjoining orifices; a vibrating tongue covering and controlling said orifices and an air tight chamber completely surrounding the portions of said pipes in which the adjoining orifices are formed.

2. In a sound producer, an air supply pipe and an emission pipe axially in line, said pipes having adjoining rectangular orifices, a vibrating metal tongue controlling both said orifices, a partition located between the pipes, and a valve in said partition for permitting the return of air from said emission pipe to said supply pipe.

In testimony whereof I have signed my name to this specification in the presence of two subscribing witnesses.

LOUIS SAVART.
